COMBINATION SHELF AND CLOTHESRACK

Filed Oct. 28, 1927

INVENTOR

M. M. OLANDER

BY *M. M. Olander*

ATTORNEY

UNITED STATES PATENT OFFICE.

MILTON M. OLANDER, OF CHAMPAIGN, ILLINOIS.

COMBINATION SHELF AND CLOTHESRACK.

Application filed October 28, 1927. Serial No. 229,373.

My invention relates to improvements in combination shelves and clothes racks, and it consists in the combinations, constructions, and arrangements herein described and 5 claimed.

An object of my invention is to provide a combination shelf and clothes rack which may be readily inserted in a clothes closet or a clothes locker, and by means of which 10 the carrying capacity of the locker or closet is increased.

A further object of my invention is to provide a device of the type described by means of which clothing may be held free 15 from the walls of the locker.

A further object of my invention is to provide a device of the type described which is constructed of relatively thin material and is so formed that air may circulate freely therethrough, thus rendering the device 20 sanitary.

A further object of my invention is to provide a device of the type described by means of which any piece of clothing may 25 be removed without disturbing the other clothing disposed therein.

Other objects and advantages will appear in the following specification, and the novel 30 features of the invention will be particularly pointed out in the appended claims.

My invention is illustrated in the accompanying drawings, forming part of this application, in which

Figure 1 is a perspective view of the device, and

Figure 2 is a longitudinal sectional view of the device as applied to a locker.

In carrying out my invention, I provide a frame 1 substantially rectangular in contour and formed of a relatively thin material. Supporting members 2, 3 and 4 extend between side walls 5 and 6 of the frame 1 and are provided with downwardly extending integral portions which are rigidly secured to the sides 5 and 6 by means of rivets or bolts 7. A plurality of clothes hooks 8 are secured at spaced-apart points to the supporting members 2, 3 and 4.

A tray 9 is disposed between the supporting member 2 and the front 10 of the frame and between the side walls 5 and 6. Openings 11 and 12 are disposed in the side walls 5 and 6, respectively, for a purpose herein-after described.

Let us assume that the device is to be applied to a locker, indicated generally at

18, which is of standard size. The frame may be constructed to conform to the inner dimensions of the locker 18. By placing the device within the locker, as shown in 60 Figure 2, the frame may be rigidly secured to the locker by placing the bolts or rivets through the openings 11 and 12 and through the openings provided in the locker for the usual shelf. In this manner, the device 65 may be rigidly secured within the locker. The size and shape of the device may be varied to agree with the size of the locker in which it is to be disposed. The number of hooks 8 may also vary in number according 70 to the size of the locker.

When the device is in place, it will be noted that the tray 9 is positioned adjacent the door 14 of the locker. This tray is arranged to receive small articles, such as keys, 75 watches, pocketbooks, or any other articles which the user wishes to dispose therein. The hooks are so arranged that the clothes may be hung in rows and positioned away from walls of the locker.

When wet garments, such as track suits or bathing suits, are placed within the locker, they may be suspended from the hooks 8. In this manner, air may circulate freely through the locker between the supporting members 2, 3 and 4, and the wet garments may dry properly and will not mildew as would be the case if they were suspended from hooks so that they would engage with 85 the walls of the locker.

Furthermore, wet garments, such as track suits, bathing suits, or the like may be suspended from two, three or four of the hooks 8. In this manner, the wet garments are held in somewhat of a circular position, allowing the air to pass not only therearound but therethrough. The positions of the hooks 8 upon the spaced-apart supporting members 2, 3 and 4 permit a free circulation 95 of air through air openings 15 in the bottom of the locker door 14, through the locker around the garments, between the supporting members 2, 3 and 4, and through air openings 16 in the top of the locker door 14.

1 claim:

1. A device of the type described comprising a frame having side walls and a front wall and arranged to be disposed in a compartment having walls, means whereby said frame may be rigidly secured to the 110 walls of said compartment, supporting members extending between the side walls of

said frame and having downwardly extending portions arranged to be secured thereto, hooks secured to said supporting members at spaced-apart points, and a tray disposed between said front wall, said side walls and the adjacent supporting member.

2. A device of the type described com-

prising a frame, supporting members carried by said frame, T-shaped hooks carried by said supporting members and positioned at spaced-apart points, and a tray carried by said frame and integral with one of said supporting members.

MILTON M. OLANDER.
